AUDIBLE FIGURE TOY

Henry A. Blake, Newton, Mass., assignor to Blake Industries, Inc., Boston, Mass., a corporation of Massachusetts

Filed Nov. 2, 1959, Ser. No. 58,189

Term of patent 3½ years

(Cl. D34—2)

Fig. 1

Fig. 1 is a front elevational view of an audible figure toy showing the new design;

Fig. 2 is a side elevational view thereof; and

Fig. 3 is a top plan view thereof.

The back of the head, not shown, is substantially plain and follows the contour shown in Fig. 2.

The dominant features of the design reside in the portions shown in full lines.

I claim:

The ornamental design for an audible figure toy, substantially as shown and described.
